David Wilkinson of Providence County of Rhode Island,
Date Nov. 14. 1798

The schedule referred to in these Letters Patent and making part of the
same containing a description in the words of the said David Wilkinson himself
of an Improvement, to wit, A machine for cutting screws.

Specification of a machine for cutting screws, invented by David Wilkinson
of Providence in the County of Providence and State of Rhode Island.
This machine resembles a turner's lathe, fixed at the end of a large water-wheel
quidgen which has a catch on the end that takes hold of a tooth on an iron staff
of said machine, which has an iron spur wheel thereon to turn another wheel
of equal size which runs on the centre pin of the head block on which the end
of the screw-iron which is in operation - with a catch from said cog-wheel to
pass through the head of the screw to turn it. The other end of said screw
turns on a centre which slides through a head stock, which is applied to the
place where it is most convenient by a perpendicular screw through the same.
At the other end of said machine which extends eighteen or twenty feet are head
stocks, cog-wheels, and cutters - the first of which carries a guide screw
of round iron of any size or graduation. A bye staff from the first mentioned
head stock with a cog-wheel on the end gives motion to the guide screw, which
has a female screw or nut in two parts to run back by hand when unclipped -
fixed in a carriage that runs on another carriage which vibrates back and
forth on three roller or trucks, as the aforesaid guide screw moves it. In this
carriage is fixed the cutter which begins at the end and runs along as gradu-
ated by the guide screw, when drawn knock off the catch and stops of staff,
the cutter cuts the screw of any size or any number of threads wished for, and turns
itself in the same manner. The nut or female screw is cut by an iron staff
running on the centre when the male screw is cut with a cutter put through
a mortise in said staff - the nut fixed in the carriage and moved only
by the same guide screw, cuts the male screw. Upon the foregoing principle

Dec. 14, 1798

Screws of every size may be made and by their running on centres they
are perfectly true and uniform.
